SINGLE DIAL TENSION FOR BASS DRUMS

Fred Schuman, McGregor, Mich.

Application June 7, 1937, Serial No. 146,941

4 Claims. (Cl. 84—411)

This invention relates to drum tensioning devices and has for the primary object the provision of a device of this character which includes a plurality of improved tensioning elements and an operating means connected thereto, whereby all of said tensioning elements may be simultaneously operated to increase or decrease the tension on the drum heads, which saves time in the adjustment of a drum and permits such work to be more readily and accurately accomplished.

With these and other objects in view, this invention consists in certain novel features of construction, combination and arrangement of parts to be hereinafter more fully described and claimed.

For a complete understanding of my invention, reference is to be had to the following description and accompanying drawings, in which Figure 1 is a bottom plan view illustrating a drum equipped with a tensioning device constructed in accordance with my invention.

Figure 2 is a side elevation illustrating the same.

Figure 3 is a sectional view taken on the line 3—3 of Figure 1.

Figure 4 is a sectional view taken on the line 4—4 of Figure 1.

Figure 5 is a sectional view taken on the line 5—5 of Figure 4.

Figure 6 is a sectional view taken on the line 6—6 of Figure 4.

Figure 7 is a perspective view of one of the guide rollers.

Figure 8 is a fragmentary vertical transverse sectional view through the drum.

Figure 9 is a fragmentary elevation looking toward one of the finger pieces.

Referring in detail to the drawings, the numeral 1 indicates a shell of a drum, 2, the heads of the drum and 3 head securing hoops or bands to which the heads 2 are secured and each include a supporting flange 4 partly overlying the head adjacent thereto. Bearings 5 carried by the hoops or bands rotatably support an operating shaft 6 provided at one end with a hand wheel 7 and with a gear 8 at its opposite end. The gear 8 through a transfer gear 9' operates a sprocket gear 8' over which travels an endless sprocket chain 9.

Clamps 10 separably engage with the peripheral edges of the hoops or bands 3 and are preferably evenly spaced an equal distance about the drum and have formed thereon journals 11 to rotatably support tensioning shafts 12, each

including shaft sections 13 and 14 rotatably supported by a pair of spaced bearings 15 carried by the shell, one being threaded for the companion shaft 13. One of the shaft sections has a socket 16 provided with angularly related walls to receive an extension 17 on the section 13. The extension 17 has angularly related faces to match the angularly related walls of the socket 16 so that the shaft sections are slidably connected and held against rotation relative to each other. 10 A sleeve 18 loosely houses the inner ends of the shaft sections 13 and 14, being arranged between the bearing 15 and suitably held in this position while the threads of one of each pair of the said bearings matches screw threads 19 on each shaft 15 section 13. The bearing of the clamp 10 engageable with one of the hoops or bands has journaled therein a sleeve 20 having feed threads meshing with feed threads 21 of the shaft section 14. The sleeve 20 is held against endwise movement 20 in its respective bearing in one direction by a flange 22. The shaft section 13 is journaled in the bearing 11 and has secured thereto a gear 23.

Sprocket gears 24 are journaled on the flange 4 of one of the hoops or bands 3 and have the 25 sprocket chain 9 trained thereover, being at the outermost sides of the said gears 24. A gear 25 has a pinion 25' which meshes with the gear 23 while the said gear 25 meshes with a pinion 24' joined with the gear 24 so that the rotation of 30 the shaft 6 by the hand wheel 7 in one direction will bring about adjustment of the shaft sections 13 and 14 toward each other to increase the tension on the drum heads and on rotation of the shaft 6 in an opposite direction the tension on 35 the drum heads will be reduced. By the tensioning shafts 12, through simultaneous adjustment thereof, permits a drum to be tensioned evenly, accurately and quickly.

Guide rollers 26 are journaled on stud axles 26' 40 of brackets 26'' adjustably mounted on the flange 4 of one of the hoops or bands 3 and these rollers 26 engage the sprocket chain 9 at opposite sides of the sprocket gear 8'. The sleeves 20 have spring pressed snap jointed finger pieces 27 pivoted thereto which may be brought into position to permit a person to adjust the tensioning elements or shafts 12 independently of each other, the springs for these finger pieces being indicated at 27'. These finger pieces when in one 50 position engage with the clamps 10 next thereto so as to hold the sleeves rotatably supported in the journals 11 against turning movement for the effectiveness of the simultaneous adjustment of the tensioning shafts. Now when it is desired to 55

make adjustment of one of these shafts individually, the finger piece 27 will be freed from the engagement with the clamp 10 so that it can be manually operated for the turning of the sleeve 20 and thus independent adjustment with respect to one of the tensioning shafts can be accomplished by manual manipulation of the finger piece 27 for the rotation of the sleeve 20. One of each pair of bearings 15 has fitted therein a bushing 15' being fixed by a retaining screw 15'.

What is claimed is:

1. A tensioning device for a drum having a shell, drum heads mounted thereon and adjustable hoops for the said heads, comprising extensible and contractible rotatable tensioning elements disposed concentrically of and outside of said shell and each having interfitted shaft sections, one shaft section of each tensioning element having a socket provided with angularly related walls, extensions formed on the other shaft section of each tensioning element received in said socket and having faces shaped to match the angularly related walls, clamps engaging said hoops and having connection with said tensioning elements, sprocket gears associated with one of the hoops and having operative connection with certain of the shaft sections of said tensioning elements, an endless chain fitting the sprocket gear, and a single hand-operated means associated with one of the sprocket gears for imparting movement to the said chain.

2. A tensioning device for a drum having a shell, drum heads mounted thereon and adjustable hoops for the said heads, comprising bearings carried by said shell, extensible and contractible rotatable tensioning elements journaled in said bearings and each having interfitted shaft sections, one shaft section of each tensioning element having a socket provided with angularly related walls, an extension formed on the other shaft section of each tensioning element received in said socket and having faces shaped to match the angularly related walls, clamps engaging said hoops, bearings formed on said clamps and the bearings of the clamps engageable with one of the hoops rotatably supporting certain of the shaft sections, sleeves journaled in the bearings of the clamps engageable with the other hoops and threaded onto the other shaft sections of said tensioning elements, sprocket gears associated with one of the hoops and having operative connection with certain of the shaft sections, a sprocket chain connecting said sprocket gears, and a single operating means associated with one of the sprocket gears for driving the sprocket chain.

3. A tensioning device for a drum having a

shell, drum heads mounted thereon and adjustable hoops for the said heads, comprising bearings carried by said shell, extensible and contractible rotatable tensioning elements journaled in said bearings and each having interfitted shaft sections, one shaft section of each tensioning element having a socket provided with angularly related walls, an extension formed on the other shaft section of each tensioning element received in said socket and having faces shaped to match the angularly related walls, clamps engaging said hoops, bearings formed on said clamps and the bearings of the clamps engageable with one of the hoops rotatably supporting certain of the shaft sections, sleeves journaled in the bearings of the clamps engageable with the other hoops and threaded onto the other shaft sections of said tensioning elements, sprocket gears associated with one of the hoops and having operative connection with certain of the shaft sections, a sprocket chain connecting said sprocket gears, a single operating means associated with one of the sprocket gears for driving the sprocket chain, and means associated with certain of the clamps for individual adjustment of the same independently of the tensioning elements.

4. A tensioning device for a drum having a shell, drum heads mounted thereon and adjustable hoops for the said heads, comprising bearings carried by said shell, extensible and contractible rotatable tensioning elements journaled in said bearings and each having interfitted shaft sections, one shaft section of each tensioning element having a socket provided with angularly related walls, an extension formed on the other shaft section of each tensioning element received in said socket and having faces shaped to match the angularly related walls, clamps engaging said hoops, bearings formed on said clamps and the bearings of the clamps engageable with one of the hoops rotatably supporting certain of the shaft sections, sleeves journaled in the bearings of the clamps engageable with the other hoops and threaded onto the other shaft sections of said tensioning elements, sprocket gears associated with one of the hoops and having operative connection with certain of the shaft sections, a sprocket chain connecting said sprocket gears, a single operating means associated with one of the sprocket gears for driving the sprocket chain, means associated with certain of the clamps for individual adjustment of the same independently of the tensioning elements, and means for permitting adjustment of the last-named means for holding the same against individual adjustment thereof independently of the tensioning elements.

FRED SCHUMAN.
